UNITED STATES PATENT OFFICE.

ALVIN J. BASSETT AND JOHN E. SHARP, OF MILWAUKEE, WISCONSIN, ASSIGNEES TO
MILWAUKEE RELIANCE BOILER WORKS, OF MILWAUKEE, WISCONSIN.

COMBINED GAS AND STEAM GENERATOR.

1,314,630.

Specification of Letters Patent. Patented Sept. 2, 1919.

Application filed July 13, 1917. Serial No. 180,401.

To all whom it may concern:

Be it known that we, ALVIN J. BASSETT and JOHN E. SHARP, both citizens of the United States, and residents of Milwaukee, 5 in the county of Milwaukee and State of Wisconsin, have invented certain new and useful Improvements in Combined Gas and Steam Generators; and we do hereby declare that the following is a full, clear, and 10 exact description thereof.

Our invention relates to certain new and useful improvements in gas producers, of that type exemplified in Letters Patent No. 1062721, granted to W. F. Luick and A. J.

15 Bassett, May 27, 1913.

It is primarily the object of our invention to so improve the structure of the gas generating chamber so as to provide for the utilization of excess heat energy for producing steam or hot water as may be desired.

It is further an object of our invention to provide means for initially heating the water prior to its entrance to the jacket surrounding the gas generator without detracting from the efficiency of the device.

With the above and other objects in view which will appear as the description proceeds, our invention resides in the novel construction, combination and arrangement of 30 parts substantially as hereinafter described and particularly defined by the appended claim, it being understood that such changes in the precise embodiment of the herein disclosed invention may be made as come 35 within the scope of the claim.

In the accompanying drawings we have illustrated one complete example of the physical embodiment of our invention constructed according to the best mode we have 40 so far devised for the practical application of the principles thereof, in which:

The drawing illustrates a sectional elevation of a complete gas producing plant embodying the features of our invention with 45 parts broken away and parts in section to better show certain structural features.

Referring now more particularly to the accompanying drawings, the numeral 1 represents a metallic casing having secured 50 therein in spaced relation by means of suitable stay-bolts 2, a shell or casing 3 which forms the wall of the gas generating chamber 4 which is closed at its upper end by a cap or cover 5, and the lower end of shell 3 55 is flanged laterally as at 6 and secured to

jacket 1 in a water-tight joint to provide a steam or water jacket 7 which is closed at its upper end above cap 5 by a cover 8 which has in its top portion and in communication with the steam chamber a steam dome 9. A circular and inwardly tapered fuel pot 10 which is formed by two sections having their inner ends flanged and engaging the shelf or bracket 11 fixed to the inner peripheral wall of jacket 1 is disposed below the gas generator chamber 4; and supported by suitable brackets 12 secured to jacket 1 in the ash pit 13 located beneath said fuel pot, is the usual grate 14.

A communication between the gas chamber 4 and a gas delivery flue 15 is formed through the interposition of a thimble 16 that is fitted to corresponding apertures in the covers 5 and 8, the gas delivery flue being in turn connected to the head of a 75 heating drum 17. A T-section 18 of the flue has one branch that communicates with the drum bottom and another branch 19 that is coupled to a bonnet 20, the third branch being connected with extension 15' which 80 terminates in a catch-basin 21, sealed with a column of water same as bonnet 20, and provided with an overflow 22 to permit exit therefrom of sediment.

The bonnet 20 is mounted in an open 85 ended trap 23 with which it communicates by means of end ports 24, the lower end of the bonnet being sealed by a column of water. This water column is maintained at predetermined normal height under control 90 of a waste or overflow pipe 24', water being supplied to the trap 23 from a drain pipe 25 that communicates with said trap and the bottom water chamber 26 of a cylinder 27, and has intermediate its ends a three-way 95 valve 28 from which leads a drain 28'.

The crown 29 of the bonnet is provided with a depending vent pipe 30, the mouth of the same terminates slightly above the normal height of the trap water seal, the 100 vent pipe in turn, being connected to a stack 30' for carrying off the gases incidental to an initial firing of the gas generator. The bonnet 20 is also provided with a gas delivery flue 15" communicating with an 105 elbow 31 that conducts the supply of gas from the generator to the water chamber 26 of the scrubbing cylinder 27, the said elbow being arranged to discharge under a grating 32 that serves as a support for a 110

wet scouring body of filter material 33, which material is preferably stone. The upper portion of the cylinder 27 of the scouring apparatus is provided with a second grating 32' between which and the adjacent head of said cylinder is a second body of dry filter material 34 such as finely crushed stone, coal or the like, through which the gas product passes and is delivered to the point of storage or consumption through supply pipe or supply pipes 35, whereby the cylinder head being provided with a suitable hand-hold, not shown, whereby access may be had to the scouring substance. For retaining the filter material 33 in the proper wet condition, a spray 36 is disposed in the cylinder above the filter material bed, the water or liquid draining from the filter bed into the chamber 26 as will be obvious.

Passing through the steam dome 9 is a passage 37 connecting the fuel magazine 38, disposed above said steam dome, with the gas generator chamber, the same being provided with a cap closure and bottom that is controlled by gravity closing valve 39 as shown, whereby fuel charges are supplied to the pot below. The cap 8 is provided with suitable insulating material 40 such as asbestos and the like for retaining the heat in the steam chamber, and the chamber 7 is interrupted by a suitable thimble 41 that constitutes a poke hole having an adjustable cover 41' to permit the insertion therethrough of a poker (not shown) in order to settle the fuel bed or break clinkers which may form in the fuel pot. In order to provide a forced draft for the generator, an inlet 42 is provided terminating beneath the central portion of the grate and having coupled with its outer end a T-joint 43 having one branch connected with an air inlet 44 from any suitable blower (not shown) and its other end communicating with a steam jet 45.

The heating drum 17 has mounted therein near each end thereof a disk or plate 46 having secured therein the ends of tubes or flues 47 which connect the ends of said drum and permits the uninterrupted passage therethrough of the gas. The space surrounding the tubes intermediate the disks 43 forms an initial heater for the water prior to its entrance to chamber 7 of the generator and the water is supplied thereto by means of inlet 48 which has therein a control valve 49 which is automatically operated by float controlled means 50, as shown, and leading from near the top and bottom of the water space of drum 17 are the pipes 51 permitting the passage from said drum to the

chamber 7 of the water. Connected with the steam dome and the chamber 7 is a high and low water alarm column 52 provided with the usual warning whistle steam gage and sight gage, the outlet for the steam generated in chamber 7 leading from the top of the steam dome as indicated at 53.

In most inventions of this character, approximately 20% of the heat generated in the gas chamber 4 is lost, and our invention tends to eliminate this loss by utilizing such energy to generate steam which may be used for any desired purpose.

From the foregoing description taken in connection with the accompanying drawings, it will be readily seen that we have provided a practical structure which will eliminate all loss of energy thus obtaining an extremely high degree of efficiency.

It will also be readily understood that the steam and air inlets are used to start the fire or to keep up the gas supply while in operation, this being simply for a forced draft. If running on a pressure type of generator either the steam blower or volume blower can be used to keep up the pressure of gas or it may be run suction type, suction to be kept up by engines, suction fans, pressure exhausters or other suction devices.

What is claimed is:

A combined gas and steam generator comprising a gas generator chamber having a fuel pot disposed therebeneath, a steam generating jacket surrounding the sides and top of the gas generating chamber, a steam dome on the jacket, a pre-heating chamber disposed below the water level of the steam generating jacket and provided with water and gas spaces, a pipe connecting the water spaces of the pre-heating chamber with the lower portion of the steam generating jacket, an inlet pipe for the water spaces of the pre-heating chamber, a valve controlling flow of water through said inlet pipe, a flue extending from the gas generating chamber to the gas spaces of the pre-heating chamber, a delivery flue extending from said gas spaces, a level control means for the water in the jacket communicating with the steam dome and with the jacket below its water level, and an operative connection between said level control means and the valve of the inlet pipe of the pre-heating chamber.

In testimony that we claim the foregoing we have hereunto set our hands at Milwaukee, in the county of Milwaukee and State of Wisconsin.

ALVIN J. BASSETT.
JOHN E. SHARP.
